UNITED STATES PATENT OFFICE.

SYDNEY R. WYCHERLEY, OF BROMLEY, ENGLAND, ASSIGNOR TO SPICER BROTHERS, LIMITED, OF LONDON, ENGLAND.

LOOSE-LEAF BINDER.

1,398,215.

Specification of Letters Patent.

Patented Nov. 22, 1921.

Application filed March 10, 1921. Serial No. 451,244.

To all whom it may concern:

Be it known that I, SYDNEY RENODEN WYCHERLEY, stationer, a subject of the King of England, residing at 25 Holligrave road, 5 Bromley, Kent, England, have invented certain new and useful Improvements in Loose-Leaf Binders, (for which I have filed an application in England, No. 1858 of 1920, filed Jan. 20, 1920,) of which the following 10 is a specification.

This invention relates to flexible band loose leaf binders of the type wherein leaves are held by flat thongs or straps and are clamped by means of two clamping bars 15 which are drawn together by winding up the thongs or straps.

In files of this type the thongs are at one end connected to one clamping bar and are at the other end wound upon a shaft 20 mounted within the other clamping bar, such shaft being adapted to be operated by means of a key or the like. The improved binder is illustrated in the accompanying drawings in which Figure 1 is an inside elevation of the binder in its open condition, the detachable cover of the clamping bar containing the winding mechanism being shown as removed from the bar. Fig. 2 is a top view of the clamping bar and the 25 winding mechanism. Fig. 3 illustrates in section a modification and illustrates the manner in which the key is inserted into the clamping bar, Fig. 4 is a similar view showing the key in the position which it assumes 30 after the unlocking of the winding shaft. Fig. 5 is a perspective view of the key. Fig. 35 6 is a top view of the thong, Figs. 7 & 8 and 9 are sections showing three constructions of the composite thong. Figs. 10 & 11 illustrate the preferred manner of attaching the 40 thong to the winding shaft. Fig. 12 is a cross sectional view through the assembled clamping bar. In Fig. 1 the thongs 1, 1 are assumed to be attached in some suitable 45 manner to the clamping bar 2 which in turn is secured to one half 3 of the telescopic back. The other clamping bar 4 is secured to the other half 5 of the telescopic back, and carries the winding shaft 6 upon which 50 are wound the other ends of the thongs 1, 1. The shaft is mounted in such a manner that it cannot move longitudinally, but can rotate freely in its bearings, as for example those shown at 6^a. One end of the shaft is 55 provided with means by which it can be

engaged by one end of the key, which may for this purpose be flattened out as shown at 9, Fig. 2 and fit a diametral slot 10 provided in the part 11 of the key (see Fig. 5). At the other end the winding shaft is provided with a clutch member 14 which co-operates with a longitudinally movable clutch member 15, adapted to lock the shaft against rotation in one direction only. The latter is held in engagement with the member 14 60 by a spring 16 which encircles the shaft 6 and is interposed between a projection 17 of the shaft 6 and the clutch member 15. The clutch member 15 is mounted in a slide 18 which may be actuated to open the clutch in 65 the following manner. The slide 18 is provided with a projection 19 the inner end of which projects into the path forming the extension of a hole 20 provided in the hollow pin 21 inserted into the end of the 70 clamping bar and forming a pivot on which the binder cover 22 is hinged. The key is provided upon its part 23, which is cylindrical and fits, but not very tightly, the hole 20, with a reduced portion 24 and a portion 75 25 which on one side only projects laterally from the portion 24. The key may also be provided upon its cylindrical portion 23 with a notch 26 of the shape shown. In order to open the clutch and lock the clutch 80 member 15 in the open position to allow the thongs to be expanded, the key is first brought into the position indicated by dotted lines (Fig. 3) so that the part 25 passes behind the projection 19. The key is then 85 turned by 180° so as to bring the part 25 with its lateral projection into engagement with projection 19, and is then withdrawn axially into the position shown in Fig. 4, 90 whereby the clutch is opened. As a rule the 95 key is automatically locked in this position on being released, by the one sided pressure exerted by projection 19 upon part 25, but if desired a notch 26 may be provided in the key into which the edge of the pin 21 may be 100 caused to engage.

The space within the clamping bar 4 available for winding up the thong being comparatively small, it is impossible to use drums of a large size, consequently the end 105 of the thong must be fastened very close to the axis of the shaft and the thong is rather sharply bent, particularly in the windings lying close to the shaft. In order to enable the thong to withstand sharp 110

bending, the thong is made of an inner strip of brass and an outer cover of fabric or leather or similar material. In Fig. 7 the inner brass strip 27 is covered by two pieces of fabric or leather 28 sewn together at the edges 29, 29. In the construction shown in Fig. 8 the cover is made of a single piece of fabric 30, the edges being sewn together at a point 31 lying between the edges 10 of the strip 27. In the modification shown in Fig. 9, the outer cover 32 is seamless. By this combination of a very pliable but strong inner strip with an outer cover of fabric or leather, the size or thickness of the 15 thongs may be reduced to a minimum. The thong is practically non-expansible.

The thong may be attached to the shaft by providing the shaft at the portion 33 (see Fig. 3) with pins 34. The preferred 20 way of attaching the thongs to the shaft is shown in Figs. 10 and 11. The shaft is provided with two longitudinal grooves 39, 39. The thong is wrapped around the shaft and is fixed thereto by a strong clip 35 the 25 ends of which press the thong into the grooves 39.

In order to allow of easy access to the winding mechanism in the form shown in Figs. 1 and 2 the U-shaped clamping bar 30 is provided with a detachable cover 12, which may be easily slid on or off and is automatically locked by spring pins 36 mounted in the clamping bar and adapted to engage holes 37 of the cover 12. Preferably two such pins 36 are mounted on each of a plurality of common semi-circular flat springs 38.

I claim—

1. A loose leaf binder, comprising leaf 40 clamping bars, leaf holding thongs connected to one of the bars, a shaft journaled on the other bar and adapted to have the thongs wound thereon, means at one end of the shaft by which it may be rotated, and means 45 at the other end of the shaft for holding it against rotation in one direction.

2. A loose leaf binder, comprising leaf

clamping bars, leaf holding thongs connected to one of the bars, a shaft journaled on the other bar and adapted to have the thongs wound thereon, one end of the shaft having means for engagement with a key by which said shaft may be rotated, and a detachable clutch that engages the other end of the shaft to normally hold it against 55 rotation in one direction.

3. A loose leaf binder comprising leaf clamping bars, one of said bars comprising a housing, leaf holding thongs connected to the other bar and entering the housing, 60 a shaft journaled in the housing and on which the thongs wrap, said shaft having a key engaging portion at one end, and a clutch in the housing at the other end of the shaft for normally securing the shaft 65 against rotation in one direction.

4. A loose leaf binder comprising leaf clamping bars, one of said bars comprising a housing, leaf holding thongs connected to the other bar and entering the housing, 70 a shaft journaled in the housing and on which the thongs wrap, said housing having keyholes in its opposite ends, said shaft having one end adapted to be engaged with a key introduced into the adjacent keyhole, 75 and a clutch in the other end of the housing adapted to lock the shaft against turning in one direction, said clutch including a releasing means adapted to be engaged by a key entered through the adjacent keyhole. 80

5. A loose leaf binder comprising leaf-clamping bars, a roller shaft journaled on one of the bars and having longitudinal grooves, thongs secured to the other bar and adapted to wrap upon the roller shaft, 85 and spring clips embracing the shaft and having portions that press the thongs into the grooves thereof.

In testimony whereof I have hereunto set my hand in the presence of two witnesses.

S. R. WYCHERLEY.
